[57] ABSTRACT

A flange for snowmobile ski. One or more flanges are attached to each of the steering skis of a snowmobile to prevent the ski and snowmobile from sliding sideways in snow or on icy surfaces. The flange engages the snow or icy surfaces and prevents lateral movement of the ski when the snowmobile is making a turn.

SKI FLANGE

The present invention relates to an apparatus for stabilizing a ski and more particularly to a flange attached to the side of a ski to prevent it from sliding sideways.

Snowmobiles use skis as a steering mechanism. These skis function with reasonable satisfaction except when the snowmobile is turned at relatively high speeds. When this turning occurs, the skis tend to slip sideways and consequently, the driver, however skillful, loses control of his machine at these times. This loss of control is particularly noticeable when the machine is driven on icy surfaces such as in races on the frozen surfaces of lakes.

It is therefore an object of the present invention to provide a new and improved apparatus for stabilizing a ski.

It is another object of the present invention to provide a flange for a ski to prevent the ski from slipping sideways when the ski is in a turn.

The invention can be more clearly understood by reference to the specification and the drawings in which:

FIG. 1 is an isometric view of a ski flange in accordance with the invention,

FIG. 2 is a front view of the flange illustrated in FIG. 1,

FIG. 3 is a cross-sectional view of a snowmobile ski with a flange shown in FIG. 1 attached to the edge thereof and an optional second edge of the ski,

FIG. 4 is a front view of a snowmobile ski and flange, and

FIG. 5 is an alternate embodiment of a ski flange shown in FIG. 1 which illustrates a spring used to form a flexible mount for the flange.

Refer first to FIG. 1 of the drawings which shows a ski flange 11. The flange 11 has a runner 12 which forms a 90° angle with the flange side 13.

The runner 12 has a rounded leading edge 14 to permit the runner 12 to easily penetrate icy surfaces or compacted snow. The trailing end 16 of the runner 12 forms a converging line with the flange side 13 and the taper thus formed tends to permit the runner 12 to clean itself as it moves through snow and ice.

The flange 11 is mounted on the edge 17 of a ski 13. The flange side 13 is mounted flush against the top surface 19. The runner 12 extends perpendicular to the bottom surface 20 of the ski 18.

The runner 12 extends below the bottom surface 20 of the ski 18 but terminates between the bottom surface 20 and keel 21 of the ski 18. Keel 21 is a replaceable keel which extends substantially the entire length of the ski 18 from the curved front end 22 to the flat rear end of the ski 18. The keel 21 is parallel to the edges 17 and 24 of the ski 18. It was found while testing the flange 11 that the runner 12 must not extend to the bottom of the keel 21 or below the keel 21, as viewed in FIG. 3 of the drawings, or the flange 11 does not work properly. Further, the runner 12 preferably extends more than half the distance from the bottom surface 20 of the ski to the bottom of the keel 21.

The flange 11 is mounted on the snowmobile ski 18, illus-

trated in FIG. 4, at the pivot point 25 of the ski 18. The typical snowmobile 26 is mounted on the ski 18 with an intermediate leaf spring 27. Thus mounted, the typical snowmobile ski tips downward at the front end 22 when the skis are off the surface of the snow.

The flange is mounted to the ski 18 by at least two bolts 28 which extend through the ski 18 and through holes 29 of the flange 11. Thus mounted, the flange 11 provides a means for preventing the ski 18 from slipping sideways in the snow or ice as the snowmobile is making a turn using the ski 18 as the steering mechanism.

An alternate embodiment of the invention is illustrated in FIG. 3 of the drawing in which two flanges 11 are illustrated mounted on the parallel edges 17 and 24 of the ski 18. The flanges 11 are mounted directly across the ski from each other and thus enhance the stability of the ski. As a snowmobile turns, one edge of the ski tends to tip and lose contact with the snow. If this edge happens to be the edge carrying the flange 11, then some of the effectiveness of the flange is lost. This condition can be remedied by using a flange 11 on each edge of the ski 18.

A further embodiment of the invention is illustrated in FIG. 5 of the drawings which shows a flexible mounted for the flange 11. A bolt 30 is sufficiently long to extend beyond the flange side 13 so that a coil spring 31 can be mounted over the bolt 30 between the flange side 14 and nut 32. The nut 32 compresses coil spring 31 when the nut is put on the bolt 30. The coil spring 31 thus forces the flange side 13 against the top surface 19 of ski 18. When the runner 12 strikes a very hard object such as a stone, the flange 11 will move upward, as viewed in FIG. 5, against the coil spring 31 thus preventing damage to the flange 11 or to the ski 18.

The above specific embodiments and examples are merely illustrative of the principles of the invention and are not to be construed as limiting thereof since many variations thereof may be made by those skilled in the art without departing from the spirit and scope of the invention.

What is claimed is:

1. An apparatus which includes a snow ski; said ski having a curved front end, parallel edges, a top surface and a bottom surface; a keel forming a part of said ski and extending substantially the entire length of the ski; said keel located midway between the edges of the ski and extending below the bottom surface of said ski; a flange mounted on a first edge of said ski midway between said front end and back end; said flange having a runner extending perpendicular to the bottom surface of said ski and extending below the bottom surface; said runner terminating between the bottom surface of said ski and the bottom of said keel at least two bolts; said flange having a flange side which is perpendicular to said runner; said flange side is attached to said ski by said bolts; a nut for each of said bolts; and a spring mounted over each of said bolts; each of said springs being entrapped between said flange side and said nuts; said springs compressed by said nuts to force said flange side against the top surface of said ski.
